UNITED STATES PATENT OFFICE.

BURDETTE O. WAKEFIELD, OF ROGERS, ARKANSAS.

TOY.

1,118,707.

Specification of Letters Patent. Patented Nov. 24, 1914.

Application filed December 27, 1913. Serial No. 808,974.

To all whom it may concern:

Be it known that I, BURDETTE O. WAKEFIELD, a citizen of the United States, and a resident of Rogers, in the county of Benton and State of Arkansas, have made an Improvement in Toys, of which the following is a specification.

My invention is a toy or amusement device, having preferably the form of a diminutive carp or sucker, and adapted to be worn as an appendage of a watch chain or as a badge or carried in the pocket. A ribbon is wound on a roller or drum journaled in the hollow body of the device, and in practice, it bears photographs or other pictures of persons, land-scapes or other things, or is provided with printed matter of any desired character.

The ribbon roller is spring retracted, and releasable means are provided for locking the roller when the ribbon is drawn off. The means for releasing the roller when it is desired to rewind the ribbon thereon include push pins and other devices, which are located in the head of the hollow fish-like body, and may be depressed, and are operated by lateral pressure.

The details of construction of the device are hereinafter described with reference to the accompanying drawing, in which—

Figure 1 is a perspective view of the device with the hinged portion of the body shown open. Fig. 2 is a longitudinal section of a modified form of the device. Fig. 3 is a cross section on the line 3—3 of Fig. 2. Fig. 4 is a detail view illustrating the means for locking the spring door or cover of the compartment in which the ribbon roller is arranged. Figs. 5 and 6 are cross sections on the lines 5—5 and 6—6 of Fig. 2 respectively.

As before intimated, the hollow body of the device preferably simulates a small carp or sucker, but it is to be understood that the invention is not necessarily restricted to this particular form, but may have various others. As shown in Fig. 2, there are three chief parts or compartments indicated by 1—2—3, the same being formed by transverse partitions 4 and 5. In the central and longer chamber or compartment 2, is arranged a drum or roller 6, on which is wound a ribbon 7, the latter having, at its free end, a metal bar 8 provided with a central loop, and its ends projecting from the side edges of the ribbon in such manner that when the

ribbon is wound wholly upon the roller, the ends of the bar lie in notches formed in the flanges of the drum, as illustrated in Figs. 2 and 6. A retracting ribbon spring 9 (see Figs. 2 and 5) is applied to the roller 6 in such manner as to normally retract or wind on the ribbon. The projecting rear end of the roller shaft is provided with a lateral prong 6^a and serves as a thumb-and-finger piece for rotating the roller. A ratchet wheel 10 is fixed on the front end of the roller, as indicated in Figs. 2 and 3, and a pivoted spring pawl, shown at 11, which is right angular or elbow-shaped, engages the ratchet, as shown. The pawl is held normally engaged with the ratchet by means of a spiral compression spring 12, and it may be released from the ratchet by pressing upon slidable pin 13, which projects through the shell of the device and has an enlarged conical head. Directly opposite this push pin 13, that is to say, on the opposite side of the fish-like body, is arranged another push pin 14, which bears upon a pivoted elbow lever 15 that is connected with and serves to operate a slidable bar 16 (see Fig. 4), whose free end is adapted to enter a perforation in a lug 17 formed on the hinged portion 18 of the shell or body of the device (see Fig. 1).

The lug of the hinged portion 18 is adapted to enter a recess in the underside of the body, which is indicated at 19, Fig. 1. The locking rod 16 is adapted to slide in a guide-way, which will be understood by reference to Figs. 1 and 4. The rod is normally projected into locking engagement by means of the aforementioned spiral spring 12 (see Figs. 1, 3 and 4), which is arranged between the levers 11 and 15, as shown best in Fig. 3.

The fish-like body of the device may be divided in halves, lengthwise, as indicated at x, or, what may be a preferable construction, the body is provided with a hinged door or side portion 18. A plate spring 21 (see Figs. 1 and 6) is attached to the inner side of the body and its free end bears slidably against the inner side of the door or hinged portion 18, and thus tends to normally throw it open when released, by pressing upon the slidable pin 14, which effects the withdrawal of the locking rod 16. It will be seen that by the construction and arrangement of the slidable pins, they are in the same position relative to the fish-like body as the eyes of the natural fish, and that by depressing one, the locking pawl of the ratchet on the

ribbon roller may be released from engagement, and, by pressing upon the other, the door or cover of the ribbon chamber or compartment may be opened.

5 As before intimated, it is intended that the ribbon shall bear photographs or other pictures or be printed with any matter giving information or tending to provide amusement, etc.

10 What I claim is:—

A toy-like device comprising a spring drum and container therefor having the form of a diminutive fish and provided with

a spring-controlled door, a spring-operating reel arranged in said container, together 15 with ratchet-and-pawl mechanism for locking the reel against the tension of its spring, and a push-pin arranged slidably in the side of the container and operatively connected with the pawl, for releasing it from the 20 ratchet, as described.

BURDETTE O. WAKEFIELD.
